LUG STRAP

Breckinridge T. Clark, Danielson, Conn., assignor
to E. H. Jacobs Manufacturing Company, Inc.,
Danielson, Conn., a corporation of Connecticut

Application January 14, 1938, Serial No. 184,998

1. Claim. (Cl. 139—153)

My present invention is a novel and improved lug strap for use in looms, and is directed more particularly to the type of lug strap having a plug secured in the heel portion to withstand wear, and thru which the shocks between the lug strap and the picker stick of the loom are transmitted.

Heretofore in the manufacture of lug straps having plugs, such plugs have usually been made of wood, rubber, interrolled canvas, fibre, leather, or other relatively hard or hardened material and secured to the arms of the lug strap by a rivet, bolt, or bolts, which bolt is of iron, steel, or metal and passes thru both of the arms as well as the plug, having one end riveted over a washer, thus holding the plug tightly between the head and rivet.

This construction has been universally employed whether or not the arms of the lug strap were of canvas, wood, or metal, and whether or not the lug strap was of the usual U-shaped contour or with simply two arms bolted thru the plug at the heel of the strap.

While my present invention is more particularly directed to the type of lug strap being formed of inter-rolled canvas secured by adhesive and subjected to pressure and forming, yet it is within the scope of the present invention to make the U-shaped portion of the lug strap of any material other than canvas in which the features of my present invention are incorporated.

Great difficulty has heretofore been experienced in the use of a riveted lug strap since the metal rivet picks up and transmits the shocks, blows, stress, and pressures incident to the contact of the picker stick and the plug, and in the case of a plug of wood, rubber, leather, or canvas, and with the arms of the lug strap of canvas, the metal of the rivet was constantly wearing and damaging same. Also, when a rivet is used it is necessarily put thru a bored recess approximately in the middle of the plug and, hence, when the plug is worn thru until the rivet is exposed, the lug strap then becomes useless since the striking of the rivet against the wooden picker stick damages the stick. Hence, in prior riveted lug strap construction the lug strap was useless when the plug was worn half thru, unless removed and repaired.

Because of the constant hammering and the severity of the service to which the lug strap is subjected, it is impractical to rely upon glue or adhesives alone to maintain a plug in the heel of a lug strap. The constant hammering loosens the cohesion of any known binder and the drying and

the hardening of the adhesive usually renders this means of holding a plug inadequate. Therefore it has been heretofore the universal practice to rely on a metal rivet, or bolt, passing thru the center of the plug as above explained.

My present invention obviates the prior difficulties experienced with lug straps having a plug therein, and I have devised a novel process and produced a new article of manufacture consisting of a rivetless plug-lug strap, wherein substantially the entire thickness of the plug can be subjected to wear without injury or damage to the picker stick, thereby greatly prolonging the life and usefulness of the lug strap.

Furthermore, my present invention provides a rivetless lug strap construction wherein the constant hammering action between the picker stick and the plug serves to hold and force the plug more closely into contact with the heel of the lug strap in which it is fitted. These desirable features I am enabled to secure by a simple and efficient process of manufacture, in an economical manner, and without undue expense or burdensome manufacturing steps and methods.

In carrying out my invention I provide a construction of lug strap and plug wherein each is so constructed and arranged as to cooperatively interlock with the other, thus maintaining the plug in the heel of the lug strap, which interlocking construction tends to be increased and tightened by the constant hammering of the picker stick.

I carry out my present invention by providing a recess in the heel of the lug strap and constructing and arranging the plug itself to fit with in said recess and interlock therewith, both lug strap and plug being formed with cooperatively interlocking portions therefor. While I may form the heel of the lug strap either of canvas or metal by molding a recess therein to fit correspondingly a part or all of the plug structure, I may also mold or form interlocking ribs, flanges, mortices, or equivalent self-locking cooperating members both in the plug or heel. Thus a projecting rib, or ribs, flange, or flanges, mortice or dovetailed devices can be formed in the heel and cooperating recesses in the plug, or, vice versa.

Furthermore, such interlocking means are preferably formed or molded integral with the heel of the lug strap and the plug, but the same may be separate units, such as wood or fibre.

If metal morticing or interlocking members are desired to be used they should be at the extreme heel portion or in the sides out of range of the line of contact with the picker stick so as

not to damage the picker stick when the plug is worn substantially thru. This is important as one of the prime features of my present invention in providing a rivetless plug lug strap is to 5 eliminate the danger of the plug wearing thru to the metal fastening device, which would damage the picker stick.

Further advantages, novel features, and combinations will be hereinafter more fully pointed 10 out and claimed.

Referring to the drawings illustrating preferred 15 embodiments,

Fig. 1 is a plan view of my improved lug strap with plug and interlocking construction;

15 Fig. 2 is a side view;

Fig. 3 is a cross-sectional view on the line 3—3 of Fig. 1;

Fig. 4 is a cross-sectional view on the line 4—4 of Fig. 2;

20 Fig. 5 is a cross-sectional view on the line 5—5 of Fig. 2;

Fig. 6 is a perspective view showing the lug strap broken away;

25 Fig. 7 is a view in perspective of a modified form of plug;

Fig. 8 is a cross-sectional view illustrating the fitting of the plug of Fig. 7;

Fig. 9 is a fragmentary cross-sectional view of a modified form on the line 9—9 of Fig. 10;

30 Fig. 10 is a fragmentary cross-sectional view on the line 10—10 of Fig. 9;

Fig. 11 is a cross-sectional view on the line 11—11 of Fig. 9;

35 Fig. 12 is a side view of a further modification; Fig. 13 being a cross-sectional view on the line 13—13 of Fig. 12;

Fig. 14 is a fragmentary cross-sectional view on the line 14—14 of Fig. 13;

Fig. 15 is a still further modification;

40 Fig. 16 is a cross-sectional view on the line 16—16 of Fig. 15;

Fig. 17 is a cross-sectional view on the line 17—17 of Fig. 16, and

45 Figs. 18 and 19 are plan and side views, respectively, of a still further modification.

As shown in the drawings, Figs. 1 and 2 are plan and side views, respectively, of a lug strap made in accordance with any standard or desired method or construction, but preferably in 50 accordance with the reinforced lug strap construction of U. S. patent to W. I. Bullard No. 1,775,077, wherein the lug strap is formed of interlocked canvas, coated with adhesive, and reinforcing layers, and then subjected to pressure 55 and formed into U-shaped contour, having a rounded heel portion 1 and side arms 2—2, each side arm provided with slots 3—3 to receive a securing bolt. At the heel portion 1 form the lug strap, when subjected to the molding pressure, with a recessed indentation 5, being indented substantially around the heel part 1 and extending along each arm 2—2 a distance equal to the thickness of the plug which is to be fitted therein.

60 65 As shown in the drawings, this recess 5 would extend from approximately the position 6—6, see Fig. 5, around the heel part longitudinally of the lug strap, and vertically or widthwise of the strap substantially as shown in Figs. 3 and 4, 70 leaving a small extending flange 7—7 at the top and 8—8 as shown at the bottom portion in which the plug 10 is fitted.

The plug 10 in order to cooperate in size and area with the recessed portion 5 and to fit between the top flange 7 and bottom flange 8

around the recess 5 is made of appropriate dimensions and short in length so as to be automatically fitted or sprung into the recess 5; and thereupon it is held therein by the overlapping and encircling flanges and the ridge of the indentation 5 at the forward portion in each arm 2—2, as shown at 9.

Preferably the contacting faces or walls of the plug 10 and the recess 5 is fitted with adhesive to hold the same, but the interlocking or mortised construction dovetailing the plug and heel portion of the lug strap together constitutes the main retaining features, holding the plug without a rivet or other fastening means passing therethru, and enabling the plug and lug strap 15 to resist the constant pounding and hammering incident to its use without displacing the plug, giving full service and usefulness to the plug throughout its entire depth, and in no case damaging the picker stick by having it strike against an iron bolt or rivet thru the plug.

Preferably, and as herein shown, I may fill in the space at the top and bottom between the overhanging flanges 7 and 8 and the end portions of the plug 10 with any filling material 12, 25 such as an additional adhesive, which will harden into form, or plastic wood or any other suitable material.

In Figs. 7 and 8 I have illustrated a modified construction of plug wherein the plug 15 is so 30 formed and constructed to eliminate the filling material 12 just explained. In this form the plug 15 is of sufficient length to equal the width of the lug strap and is provided with a shouldered portion 16 and 17 at each end to fit in the overlapping flanges 7 and 8, respectively, and to extend smoothly flush with the top and bottom portions of the heel 1 and arms 2, thus still further interlocking the plug and lug strap together. In this form, also, a coating of adhesive will be 40 supplied to the contacting faces of the plug and lug strap.

In Figs. 9, 10, and 11 a still further modification is shown, wherein the lug strap has the heel portion 20 and arms 21 formed without a depression 5, or its equivalent; but on the contrary has the interlocking feature mainly on the plug itself. In this form the plug 22 extends throughout the entire width of the heel portion and has fitted at top and bottom an overlapping flange 23—23 secured by wooden or non-metallic pegs 24—24 which extend only partly into the plug 22 and which will not injure the picker stick if it does come in contact with them during the wearing down of the plug. If desired, the overlapping flanges 23 may be otherwise secured and may also be mortised or recessed in the top of the arms 21 and heel portion 20 to provide a flush surface, if desired.

In Figs. 12, 13, and 14 I have illustrated a 60 still further modification, wherein the lug strap 25 and arms 26—26 are recessed, as shown at 27, similar to the form of Figs. 1 to 5, and with a plug 28 fitted therein; but in addition to the interlocking and overlapping flange portions constituting the boundary of the recess 27, I mold a projecting internal rib or ridge 30 in the lug strap to dove-tail with a correspondingly formed recess 31 in the plug 28 to provide a further interlocking feature. In this form, also, filling 70 material 12, 12 is supplied as shown in Fig. 13.

In Figs. 15, 16, and 17 a still further modification is illustrated, wherein the lug strap has the heel portion 35 and arms 36 molded with the recess 5 and an encircling rib 37 interlock- 75

ing with a corresponding groove 38 formed in the plug 40 extending around the recess 5 formed therein, which groove may be and preferably is of the same extent as the flanges 7 and 8 at 5 top and bottom of the recess 5. In this form, also, filling material 12-12 is supplied to cover the ends of the plug 40, which is shorter than the width of the lug strap.

In Figs. 18 and 19 there is shown a still further modification of my plug lug strap construction eliminating rivets or metal fasteners. In this latter form I utilize a typical lug strap with a heel portion 44 and arms 45, and fit therein a plug 50 which is attached to a U-shaped leather, 15 or the like, member 47 of substantial length and with non-metallic pins 49, 49, together with glue holding the plug 50 and U-shaped strap 47 together.

Thereupon the outer face of the U-shaped strap 20 47 and inner contacting surface of the lug strap around the heel and arms are coated with adhesive and the same united, the long glued or adhering surface 51 between the strap 47 and the inner face of the lug strap giving an extremely 25 long bonded contact and provides a greatly increased union and strength between the lug strap and the plug than would be otherwise possible. While this construction does not utilize

the interlocking method yet it does provide a union free of metal rivets and capable of utilization in many instances.

Various other interlocking and morticed-like connections between the plug and the heel of 5 the lug strap may be utilized, and an iron or fibre lug strap with a recess and in which is fitted or otherwise secured independently of metal rivets, bolts, or the like, a suitable plug of yielding material can be employed within the scope of 10 my invention.

I claim:

A rivetless lug strap and interlocking plug construction, comprising a U-shaped lug strap formed of inter-rolled canvas and adhesive, having a depression in the U-portion extending substantially throughout the entire area of said U-portion and along each arm, providing relatively thin inwardly extending flange portions equal to the normal width of the lug strap at said U-shaped 20 portion, a plug adapted to cooperate with said lug strap and to fit within said depression, said plug being constructed and arranged to be retained by the inwardly extending top and bottom flange portions, said plug and lug strap being 25 retained in interlocking operative position independently of any rivets.

BRECKINRIDGE T. CLARK.
